(74) Attorney, Agent, or Firm — Fish & Richardson P.C.

(57) **CLAIM**

I claim the ornamental design for a machine tool, as shown and described.

DESCRIPTION

FIG. 1 is a front perspective view of the machine showing my new design;

FIG. 2 is a front elevation view thereof;

FIG. 3 is a back elevation view thereof;

FIG. 4 is a right side view thereof;

FIG. 5 is a left side view thereof;

FIG. 6 is a top plan view thereof; and,

FIG. 7 is a bottom plan view thereof.

1 Claim, 7 Drawing Sheets
